UNITED STATES PATENT OFFICE.

NATALE MARTINO, OF NEW YORK, N. Y.

NECK-PROTECTOR.

1,274,067.

Specification of Letters Patent. Patented July 30, 1918.

Application filed May 23, 1916. Serial No. 99,301.

To all whom it may concern:

Be it known that I, NATALE MARTINO, a citizen of the United States, residing at New York, in the county of Bronx and State 5 of New York, have invented certain new and useful Improvements in Neck-Protectors, of which the following is a full, clear, and exact description.

The object of my invention is to provide 10 a protector for the neck of a person for use during the operation of cutting the hair and which is designed to effectually prevent the hair cloth from touching the neck of the person during such operation.

15 In the cutting of a person's hair, it is the practice to spread a cloth over the clothing of such person to keep pieces of hair from falling thereon. A part of this hair cloth is drawn about the neck of the person to prevent clippings of hair from falling down upon his neck.

20 The cost of laundrying hair cloths makes it necessary to use the same on more than one occasion. It is, therefore, readily apparent that any infection that may lodge upon the neck part thereof will be transmitted to the next person about whom the cloth is placed.

25 The present article will be inexpensive to manufacture and consequently a new one may be provided for each person presenting himself to have his hair cut. It may be and preferably is made of cotton or other material of soft fibrous nature which will 35 catch and effectually prevent clippings of hair from slipping down the neck.

30 Referring now to the drawing:

Figure 1 is a view illustrating the application of the article to the neck of a person 40 and showing the smaller flap in raised position.

Fig. 2 is a top plan view of the article.

Fig. 3 is a sectional view of the line 1—1 of Fig. 2, and

45 Fig. 4 is another sectional view on the line 2—2 of Fig. 2.

The sanitary protecting article consists of a flap member 1 which is adapted to fit upon the shoulders and neck of a person and an 50 other flap member 2 which is adapted to fold over the flap member 1. The said flap members may be sewed or otherwise joined together preferably at the inner edges 7

thereof. In practice I prefer to make the upper flap member 2 shorter than the lower 55 flap member 1. In adjusting the article about the neck of a person, preparatory to placing the hair cloth 3, the ends are adapted to overlap as indicated in Fig 2. This insures proper adjustment in each case. When 60 the desired adjustment has been secured the tab 4, having a gummed surface, is stuck to the flap against which it lies and holds the article in place while the cloth is being 65 adjusted.

In order to hold the flap members apart, to facilitate placing the hair cloth in position, members or struts 5, made of pasteboard or other stiffened material, are secured to the flap member 2. In the drawings the 70 members 5 are shown passing through slits 6 in the flap 2. It will be apparent that the members 5 may be secured in either flap member. The lower ends of the members 5 are not attached but merely rest against the 75 flap 1 when the flap 2 has been raised. They remain in this adjustment until touched by the hair cloth when the free ends are displaced inwardly, that is, toward the inner edge of the ring, permitting the flap member 80 2 to rest down upon the hair cloth.

It is apparent that adjustment of the article may be effected without the use of the tab 4 for when the hair cloth is drawn in place the desired tightness may be obtained 85 in adjusting the hair cloth. It is also apparent that adjustment of the article may be secured without the use of the members 5, though they facilitate such operation.

What I claim is:

1. A neck protector for the purpose described, comprising two flat annular layers or flaps arranged concentrically one on the other with their inner edges united, forming a ring capable of being opened upon said 95 inner edge as a hinge, and a plurality of struts, carried by one of said flaps to bear on the other flap and thereby hold said flaps apart and displaceable to permit the flaps to come together; said ring being split to 100 permit circumferential adjustment by inserting one end into the other when the ring is placed around the neck.

2. A neck protector for the purpose described, comprising two flat annular layers 105 or flaps arranged concentrically one on the

other with their inner edges united, forming a ring capable of being opened on said inner edge as a hinge; said ring being split to permit circumferential adjustment by inserting one end into the other when the ring is placed around the neck, and one end being provided with a gummed portion

which can be stuck to the other end to hold the two ends in adjusted position with the inner edge of the ring in close contact with the neck of the wearer.

In testimony whereof I affix my signature.

NATALE MARTINO.
